poration of Florida

Application September 3, 1936, Serial No. 99,302

26 Claims. (CL 240—214)

This invention relates to lenses and light projectors, and more particularly to their combination with and adaption to sewing machines.

The operation of sewing machines requires constant application to close work. At night under average or poor illumination the worker is subjected to much physical and eye strain with a resulting lessening of efficiency and health. To eliminate this condition by providing means for correctly illuminating the work tables of sewing machines is the principal purpose of this invention.

Another object of the invention is to provide a refractor suitable for properly illuminating the table of a sewing machine.

A further purpose of the invention lies in the production of a refractor which when placed on or within a sewing machine will project a beam having its most intense portion at the needle or in a small area about the needle on the work table of the machine.

Still another object of the invention is to control and refract a maximum of the light rays from a source in downward directions toward the needle of a sewing machine thus efficiently illuminating the working point.

A further purpose of the invention is to illuminate the sewing machine table without glare in the eyes of the workman.

Another object of the invention lies in the provision of different lenses, reflectors and light projectors which will be suitable for mounting on different types of sewing machines.

Still another object of the invention is to provide light projectors adjustable in position and efficient in operation for use with sewing machines.

Another purpose of the invention is to provide refractors and light projectors for use with sewing machines harmonizing with the appearance of the machines and adding to their attractiveness.

A further purpose of the invention is to provide refractors and projectors which will cheaply render adequate illumination for close work on sewing machines.

To aid a fuller understanding of the invention the accompanying drawings are included in which Fig. 1 is perspective view of a baby model sewing machine having mounted on its front side a refractor embodying the invention.

Fig. 2 is a bottom view of the refractor alone.

Fig. 3 is a vertical central section of the refractor taken on line 20—20 of Fig. 2.

Fig. 4 is a vertical section of the refractor with hood added taken on line 21—21 of Fig. 3.

Fig. 5 is a diagrammatic representation showing the refractor in section and illustrating the paths of light rays from a source before and after refraction.

Fig. 6 is a perspective view of a portion of a sewing machine on which is mounted a light projector adjustable in directions of light output.

Fig. 7 is a vertical central section of another lens and reflector embodying the invention showing directions taken by light rays from a source before and after refraction and reflection.

Fig. 8 is a diagrammatic representation of the beam pattern on the table produced by the projector in Fig. 7.

Fig. 9 is a front elevation of still another lens embodying the invention.

Fig. 10 is a horizontal sectional view of the lens taken on line 22—22 of Fig. 9.

Fig. 11 is a section of the lens taken on line 23—23 of Fig. 9 including a reflector and housing with directions of light rays from a source before and after refraction.

Fig. 12 is a diagrammatic representative of a beam pattern on the table produced by the projector in Fig. 11.

Fig. 13 is a vertical central section of still another lens embodying the invention drawn to scale half size with dimensions shown in inches.

Fig. 14 is a front elevation of the lens shown in Fig. 13 enlarged.

Fig. 15 is a vertical section of the lens taken on line 123—123 of Fig. 14 and enlarged.

Fig. 16 is a vertical diagrammatic central sectional representation of the lens with light source and reflector added.

Fig. 17 is an enlarged vertical central section of the projector in Fig. 16 showing the paths of light rays from a source before and after refraction.

Fig. 18 is a diagrammatic representation of a beam pattern on the table produced by the projector in Fig. 16.

Fig. 19 is a section of a flat lens which may be used in place of the refractor shown in Fig. 3.

Referring more particularly to the drawings Fig. 1 portrays a refractor 24 embodying the invention mounted on the front side of a small sewing machine 25. Surmounting the refractor 24 is a semi-cylindrical hood 26 at the rear end of which is a cylindrical projection 27 which serves to house the socket for an incandescent lamp.

The details of the refractor construction are clearly shown in Figs. 2, 3, and 4. In designing

the refractor an incandescent filament source of light is located at the point 28 in Fig. 3. From a point 29 located on the horizontal line H—H containing the light source arcs 41 and 42 are drawn with radii R1 and R2 respectively. These arcs are merged into the horizontal straight lines 41 and 42 which form the inner and outer sides of the refractor element of revolution. On the outside element 42 straight side prisms 30—35 inclusive are formed each having the same width 43 but each differing from the others in height and refractive angles. Straight line prisms 36—40 inclusive and 50—52 inclusive are formed on the inner side 41 of the refractor element 24. All of these prisms are identical in width 43 but only prisms 40, 50, 51, and 52 are alike in height and refractive angles. Prisms 36, 37, and 38 each differ from the others in these respects.

The element of the refractor 24 formed as above described is then revolved approximately 90° vertically about the horizontal axis H—H, and approximately 45° on each side of the vertical V—V as shown in Fig. 4. The shape of the refractor is then changed by the formation of a flat vertical side 44 extending approximately to the horizontal plane containing the axis of revolution. The rear portion of one side is continued still higher to form flat vertical projections 45 with the slot 46 between them, Fig. 3.

Upon the forward spherical end of the refractor 24 thus formed are placed vertical flutes 53—57 inclusive shown in Fig. 2. The center flute 53 has the largest radius. Flutes 54 and 56 have equal and smaller radii and flutes 55 and 57 have equal and still smaller radii.

The complete refractor is essentially a semi-cylindrical one open at the rear end 47 Fig. 5 and closed at the front end by a semi-spherical section containing external vertical flutes. External straight prismatic zones of refraction are formed on the under portion perpendicular to the flutes and internal straight prismatic zones of refraction are formed at the rear end of the refractor.

In order to mount the refractor on a sewing machine a metal hood 26 Fig. 4 having the same general shape as the refractor is first affixed to the machine by means of the screw 48. Referring to Figs. 1 and 4 a rectangular, spring metal plate 58 is fastened to the hood 26 by means of rivets 49. An incandescent tubular lamp 60 is inserted in the socket 27 at the rear end of the hood 26. The refractor is then slid up into place the slot 46, Fig. 3 providing room for the screw 48 and the spring clip 58 fitting snugly about and under the flange 59 on the refractor holding it firmly in place. The horizontal pressure produced by the clip 58, on the projections 45, Fig. 3 prevents any displacement of the refractor without first releasing the clip 58.

Fig. 5 illustrates the action of the refractor in controlling light rays whose paths are shown dotted. It will be seen that internal prisms 51 and 52 refract the incident rays traveling downwardly and to the right in such manner that they emerge at angles closer to the vertical although still moving slightly to the right. Prisms 50, 40, and 39 throw the emerged rays successively further and further to the left. Prisms 30—38 inclusive converge the light rays toward the position of the needle 62 on the sewing table 61. The spherical fluted portion of the refractor projects light rays to the left of the needle, the flutes spreading them toward and away from the worker. The refracting zones control and form a beam approximately 90° of solid angle in direc-

tions to and from the vertical plane containing the axis of the refractor. Thus the working table is illuminated fully by a beam having its most intense portion in a rectangular area about the needle where it is most needed. None of the light is above the horizontal and therefore cannot create glare in the workman's eyes which are above the refractor. The flat lens shown in Fig. 19 may be used in place of the refractor 24.

The refractor with minor changes in design and size may be shifted in position, placed in front or behind, on larger or smaller machines and may even be incorporated in the lower part of the sewing machine arm 25 and still accomplish its purpose of producing a better light distribution on the work table. The appearance of the refractor as above described is neat and attractive, completely harmonizing and adding to the appearance of the sewing machine.

Another means of satisfactorily lighting the machine table is to mount a light projector entirely separate from the machine proper. This can be done for example as shown in Fig. 6. Here a light projector consisting of a paraboloidal housing 63 and a lens 64 are mounted on the end 25 of a tubular arm 65 at the top end of which is located a universal ball and socket joint 66 supported in the arm 67 which is in turn supported on the sewing machine table 61. The universal joint 66 allows adjustment of the light beam in any direction within approximately 180 spherical degrees. With this arrangement the workman can adjust the light beam as best suited to his particular needs. The tubular arms supporting the projector form a convenient channel for the lead in wires to the incandescent lamp within the projector hiding them from sight and adding to the appearance of the unit. The arms supporting the projector may be affixed to the sewing machine 25 if desired or may be supported in any other 40 convenient manner.

One embodiment of the projector used above is shown in Fig. 7 in vertical central section. Here the lens 64 consists of concentric inner and outer spherical surfaces 73 and 74 respectively. Formed on the inner surface are the annular refracting zones 68, 69, 71 and 72 and the bull's-eye 70. The rear apices of said refracting zones fall in a spherical surface concentric with those of the inner and outer faces of the lens. Prism 72 is straight in section but prisms 68, 69, and 71 have curved incident sides formed by radii successively shorter from top to bottom. The centers for radii R68, R69, and the radius of the bull's-eye R70 lie on the axis of revolution of the lens section H—H while the center for the radius of curvature of prism 71, R71 lies below the axis of revolution. The substantially paraboloidal housing 63 retaining the lens is plated and polished or otherwise provided with an inner surface of high reflecting power. The resulting paths of rays in accordance with the well known laws of reflection and refraction are depicted in Fig. 7. Rays from the source 28 reflected by the housing are shown dotted while those which are directly received on the lens without previous reflection are shown in full line. These latter it will be noticed emerge from the lens converging slightly toward the axis of revolution H—H when refracted by the upper portion of the lens. Those refracted by the lower portion of the lens converge much more rapidly toward the axis of revolution resulting in an asymmetric beam. The substantially parallel rays, striking the lens from the reflector housing, are, as shown, re- 75

fracted by the lens emerging at highly convergent angles, and cross the axis of revolution diverging rapidly.

When the projector is suspended above the table at a suitable height the beam pattern on the table 61 is as represented in Fig. 8. Here again 62 represents the position of the needle. The intense portion of the beam consisting of rays which are refracted only surrounds the needle 62. Of this portion the part 75 comes from the lower portion of the lens and is behind the needle. The area 76 is intensely lighted by refracted rays only from the upper portion of the lens and is between the needle and the workman. Surrounding the intense portion of the beam is the lower intensity area 77 produced by rays both reflected and refracted which supply general illumination on the table. This beam pattern is ideal in distribution having the intense light exactly where desired about one-third back of the needle and two-thirds ahead of it and as previously explained the workman can adjust the position of the projector to suit his requirements and taste.

The lens above described is approximately three inches in diameter. The invention, however, is not limited to this particular size or shape. The paraboloidal reflector can be changed in shape without materially altering the general illumination obtained. A portion of it may even be made diffusely rather than specularly reflecting without sacrificing and perhaps bettering the characteristics of the beam.

Another lens 78 embodying the invention which may be substituted in the projector for the one above described is shown in Figs. 9, 10, and 11. This lens is round having a flat rear surface upon which are formed vertical flutes 95, Fig. 10 for the purpose of changing the round beam pattern 40 into a rectangular one. Upon the outer surface of the lens are formed horizontal straight prismatic refracting zones 81-92 inclusive. In the center of the outer surface of the lens 78 are formed annular prismatic zones 93 and 94 differing from each other in refractive angles. The corresponding horizontal prisms of the upper half of the lens are similar to those of the lower half thus giving a symmetrical beam but each prism of one portion of the lens differs from every other 50 of the same portion in refractive angle. Thus prism 86 differs from each of prisms 81, 82, 83, 84, and 85, but is exactly the same as prism 92 in the lower half of the lens. The prisms increase in refractive power the further they lie 55 from the center of the lens. The insides of all prisms are parallel to the paths of rays through the lens in their respective positions. This features causes all of the rays from the source proceeding directly to the lens to be efficiently refracted in the desired directions without production of any stray light refracted from the inner sides of the prisms.

In Fig. 11 the lens is assembled in a cylindrical housing 96 flanged at one opening to contain it. A wire retaining ring 97 holds the lens in place. A spherical reflector 95 having its center at the focus 28 of the lens is also used. The inner forward portion of the housing 96 is polished to form a reflecting surface and the whole unit 70 mounted in similar manner to the projector shown in Fig. 6. In Fig. 11 the solid lines represent paths of rays directly striking lens from the source 28 which is placed at the focus of the lens and the rays reflected by the spherical reflector. These rays emerge concentrated and

parallel and form the intense portion 98 of the beam pattern shown in Fig. 12. Here 62 again represents the position of the needle on the sewing table 61. The dotted lines Fig. 11 represent the paths of rays striking the housing which are 5 reflected and refracted to emerge from the lens at widely diverging angles to form the low intensity portion of the beam pattern 99 in Fig. 12. If the housing is made diffuse reflecting, a better beam is obtained. The oval shape of the beam 10 is occasioned by the vertical flutes 95 previously mentioned.

Still another lens embodying the invention and which may be substituted for the lenses above described in a separate projector is shown 15 in Figs. 13-17 inclusive. Referring to Fig. 17 more particularly, the lens 100 is shown in section. The mechanics of its design consists in choosing a rectangular vertical section 100 and forming at its ends the rearwardly projecting 20 flanges 101. A circular arc 102 is drawn on the outside with radius R12 and center on the horizontal H—H containing the focus 28. Two prisms 103 and 104 are drawn on the insides at its top. The incident sides of these slope 2° away 25 from the horizontal to allow withdrawal of the manufacturing plunger. These prisms are made total internal reflecting by forming their upper sides with long radii R13 and R14 having centers below and to the right of the lens. Two similar 30 prisms 105 and 106 are constructed on the bottom of the inner surface these having reflecting sides formed by still longer radii R20 and R19 above and to the right of the lens. Below prism 104 is constructed the refracting prism 105 having a short radius with its center on H—H. A similar prism 108 is formed below having a slightly longer radius but with center on H—H. Refracting zones 106 and 107 are then formed by drawing arcs with unequal radii R16 and 40 R17 having different centers in H—H. R17 being the longer of the two the centers for all radii are shown in $\frac{1}{2}$ scale position in Fig. 13.

The section as above formed is revolved 180° about the horizontal H—H as an axis to form 45 an asymmetric lens with upper portion differing from lower.

If desired horizontal flutes may be added on the outside face of the lens as shown in Figs. 14 and 15. Flute 113 is the only simple radial flute 50 and is formed on the bull's-eye 102 with radius of curvature R23. Flutes 112 and 114 are transitions between flutes and prisms having sections which are straight lines merging into arcs with radii R22 and R24 respectively. Of these two 55 the latter is the longer being on the upper portion of the lens. The straight portion of the external surface contains five equal flutes 111 which are also partially prismatic. Their radial surfaces are formed with radius R21. 60

The functions of these prisms is to spread the beam vertically. In accomplishing this purpose the prismatic portions of the flutes tend to converge diverging rays toward paths substantially parallel with the horizontal H—H. The radial 65 portions of the flutes diverge the light vertically up and down, flute 112 causing slightly more divergence than flute 114. The diffusing nature of the flutes tends to even the intensity of the beam and eliminate prism striations. 70

The lens 100 may be assembled in a projector as shown in Fig. 16. The housing here consists of a semi-spherical upper portion 115 formed by the revolution 180° about H—H of an arc having radius R30 and center 130 below H—H and 75

ahead of light source 28. The lower portion 117 of the housing is semi-spherical with a counterpart radius R31 and center 131 above H—H and ahead of the light source 28. A cylindrical portion 116 is formed at one end to hold the lens flange 101 while a smaller cylindrical portion 118 is turned at the other end to house the socket for lamp 60.

The dotted lines in Fig. 17 illustrate the paths 10 of light rays before and after refraction by lens 100. Internal reflecting prisms 103, 104, 109, 110, it will be noticed produce rays diverging from 15 H—H diverging at slightly greater angles from the lower portion of the lens than from the upper. Refracting zones 105 and 106 take direct light from the source 28 and cause it to emerge 20 in paths practically parallel with the axis of revolution H—H, while rays controlled by zones 107 and 108 emerge at small divergent angles 25 with H—H. The net result is to produce a concentrated beam which is asymmetric tending to wider spread and less intensity in the portion 30 produced by the lower half of the lens. The inner sides 115 and 117 of the housing being plated and polished to form a reflecting surface produce 35 a general widespread illumination of low intensity surrounding the more concentrated portion of the beam. Light from upper portion 115 is reflected downwardly undergoes refraction and emerges from the lens downwardly at large 40 diverging angles with H—H. Similarly light reflected by the lower portion of the housing 117 diverges upwardly at large angles.

The resulting beam pattern is clearly shown 35 in Fig. 18 where again 61 represents the sewing table and 62 the position of the needle. It will be noticed that when the projector is placed as in Fig. 6 and adjusted the very intense smaller portion of the beam 119 from the upper half of the lens surrounds the needle. The slightly lower intensity and larger portion of the beam 40 from the lower half of the lens 120 is in front of the needle on the work about to undergo the sewing operation while the low intensity general illumination 121 proceeds from the reflector. It is the flutes previously mentioned which 45 produce the elongated characteristics of the beam pattern. Should it be chosen to leave them off, the pattern would consist of two semi-circles of 50 high intensity light of different radii surrounded by two semi-circles of low intensity light of different radii. However, the elongated oval shaped beam is more desirable as explained in connection with the projector described in Fig. 7.

55 Should it be desired to make both halves of the lens alike, the resulting beam pattern will of course be symmetrical.

While a detailed portrayal has been given of some of the forms the invention may take not only in its optical characteristics but also its 60 mechanical features, it is not intended to limit the invention to the above description. The efficiency in quantity and quality of illumination obtained, and the beauty and harmony of appearance of the small projectors described will not be sacrificed in the design of larger ones for use on larger sewing machines. Changes in the 65 number of prisms placed on the refractor or changes in refractive angles, curvatures and centers of curvatures of prisms and lens to produce a similar type of beam when projectors are changed in mounting heights or otherwise 70 changed in position may be made without departing from the spirit of the invention and the scope of the appended claims.

I claim:

1. In combination with a sewing machine, a light projector mounted thereon, including an electrically energized light source within said projector and a lens, said lens having light control means to direct a restricted and concentrated beam of light downwardly upon the needle working position of said machine, and other means to allow light to pass therethrough to provide light of lesser intensity around the area illuminated by the concentrated beam.

2. In combination with a sewing machine, a light projector mounted thereon, including an electrically energized light source within said projector and a lens, said lens having light control means to direct a converging concentrated beam of light downwardly upon the needle working position of said machine, and other portions to allow light to pass therethrough to provide light of lesser intensity around the first mentioned beam.

3. In combination with a sewing machine, a light projector mounted thereon, including an electrically energized light source within said projector and a lens, said lens having light control means to direct a beam of light, the cross section of which is elongated in a direction substantially in line with the work path of the machine, upon the needle working position of said machine, and other portions to allow light to pass therethrough to provide light of lesser intensity around the first mentioned beam.

4. In a sewing machine, means for illuminating that area of the machine including and surrounding the needle; said means including a light source and refractor, said refractor having a light control zone so constructed as to concentrate a beam of light of greater intensity on said area and other portions so constructed as to produce a divergent beam of lesser intensity to 40 illuminate a relatively larger area about the first mentioned area.

5. The combination with a sewing machine, of a prismatic refractor mounted on the machine, a light source therefor, the refractor including means to divide light rays passed therethrough, a centrally located section of said means refracting a portion of the light into a concentrated beam of maximum intensity to illuminate a particular part of the machine, and another section of said means, located adjacent the central section, refracting divergent beams of less intensity to illuminate parts surrounding said part of the machine.

6. In a sewing machine, a plane work table 55 surrounding a minor area for mechanical operation upon material guided thereto, means for illuminating said minor area and a surrounding area on said work-table, the minor area receiving the most intense illumination from said means, 60 said illuminating means being mounted above said work-table and including a lens, a light source in the rear of said lens and light control zones so formed on said lens that light from said source is partially concentrated at said minor area along the path of travel of work on said machine, while light passing through the remainder of the lens is spread over said surrounding area.

7. A controllable mechanism including a plane 70 work-surface surrounding a minor area for mechanical operation upon material guided thereto, means for illuminating said minor area and a surrounding area on said work-surface, said illuminating means being mounted above 75

said work-surface and including a lens, a light source behind said lens, prismatic surfaces formed in said lens and so oriented relative to each other as to direct a concentrated light beam 5 and to elongate said light beam substantially in the direction of travel of material to be worked upon and for producing a light of lesser intensity surrounding said elongated area.

8. The combination with a horizontally disposed work surface across which work is to be fed, of a light source positioned above said surface, a reflector enclosing the upper side of said light source and a prismatic refractor enclosing the under side of the light source and having 10 light control zones to direct its rays downwardly within an area substantially less than that of the work surface, one of said zones acting to project a concentrated light from said source upon a relatively small area of the illuminated portion 15 of the surface, said area being elongated substantially in line with the path of travel of the work, and other of said zones acting to illuminate with a lesser intensity a relatively larger area of the illuminated portion of the surface about said 20 concentrated beam.

9. In combination, a controllable mechanism having a definite working station and means for projecting an intense light of relatively small area upon said working station and a light of 25 relatively less intensity but covering a substantially greater area, immediately adjacent said working station and surrounding said area of intense light, both of said light areas being elongated in the direction of and substantially 30 in line with the path of travel of work to be fed to said working station.

10. In a machine for working upon material fed thereto, a definite working station across which work is to be fed, means for projecting an intense 40 light covering a relatively small area at said working station, the intense light being divided into a plurality of immediately adjacent zones of varying intensities; and a light beam of relatively less intensity bounding the intensity illuminated area.

11. A manually controllable mechanism including a plane work-table surrounding a minor area of mechanical operation upon material 50 manually guided thereto, means for illuminating said minor area and a surrounding area on said work-table, the minor area receiving the most intense illumination from said means, said means including a lens so mounted that its axis is 55 parallel to the work-table, a light source mounted on said lens' axis, prismatic surfaces formed in the lens transverse of its axis and so oriented relative to each other that light from said source is concentrated about said minor area while light 60 passing the remainder of the lens is spread over said surrounding area.

12. A semi-cylindrical lens with horizontal axis of revolution, open at the top and one end, a spherical portion closing the other end, and internal 65 and external prisms transverse to the axis of revolution formed upon the cylindrical portion.

13. A semi-cylindrical lens with horizontal axis of revolution open at one end and closed at the 70 other by a spherical portion, a reflector, said lens having a plurality of inner and outer prismatic zones transverse to the axis of revolution of different refractive powers so formed on said cylindrical portion that light projected by said 75 reflector from a source passes through said lens

for concentration in one zone and diffusion in an adjacent but larger zone.

14. In combination, a sewing machine including a work surface and a light projector mounted in such manner as to effectively illuminate the 5 work surface of said machine with a beam having its highest intensity in the small area surrounding the needle of said sewing machine, said light projector comprising a lens whose axis of revolution is horizontal a plurality of prismatic 10 zones transverse to the axis of revolution formed upon said lens, and a light source within the axis of revolution of said lens.

15. In combination with a light source, a semi-cylindrical lens with horizontal axis of revolution, 15 open at its top and at one end and having a substantially spherical portion at its other end, and internal and external prisms transverse to the axis of revolution formed on the cylindrical portion, said prisms being arranged to form adjacent light control zones, one of said zones being constructed so as to project a concentrated beam of light of maximum intensity from said source and the other of said zones so as to project diffused light of a relatively larger area and 20 lesser intensity about the first mentioned light beam.

16. A light projector comprising a lens having a semi-cylindrical portion with horizontal axis of revolution, a light source within said axis of 30 revolution, a housing above said lens and having a reflecting surface adapted to direct light from said source downwardly of said lens, and a plurality of prismatic zones formed on the said lens transverse to said axis of revolution so that the 35 projected light is concentrated in one zone and diffused in an adjacent but larger zone that is substantially symmetrical with respect to said concentrated zone.

17. A light projector comprising a lens having a semi-cylindrical portion with a horizontal axis 40 of revolution, a light source within said axis of revolution, a housing above said lens and having a reflecting surface adapted to direct light from said source downwardly of said lens, and a plurality of prismatic zones formed on said lens 45 transverse to said axis of revolution, so that the projected light forms an asymmetrical field having immediately adjacent zones of concentrated light of different intensities and a symmetrical zone of diffused light of a lesser intensity surrounding said concentrated zones.

18. In a sewing machine, a light projector mounted thereon, said projector comprising an apertured housing with an internal reflecting surface substantially paraboloidal in shape, a light source at the focus of said reflecting surface, and a lens, closing the aperture of said reflector housing, having a plurality of annular refracting zones, prismatic and toroidal in shape, of different curvatures and centers of curvature, so formed upon the inside surface of the said lens as to converge the direct rays from said light source toward the optical axis of said projector, a greater convergence being produced by one-half of the lens than by the other.

19. In combination: a sewing machine, a light projector mounted above said machine comprising: an apertured housing having an internal reflecting surface, a light source at the focus of said reflecting surface, and a lens closing the aperture of said housing, said lens having a plurality of internal annular refracting zones, of different curvatures and centers of curvature, and so related as to converge the direct rays from the 75

light source toward the position of the needle on the table of the said sewing machine.

20. In a sewing machine, a light projector including a lens, said lens having a plurality of refracting zones and a plurality of total reflecting zones, one portion of said lens differing from a corresponding portion and each refracting and reflecting zone differing from the others, said zones being oriented relatively to one another so as to project a concentrated light field about the needle of said machine.

21. In a sewing machine, a lens having a plurality of refracting zones and a plurality of total reflecting zones, the upper portion of said lens differing from the lower and each refracting and reflecting zone differing from the others, toroidal surfaces on said zones differing in curvature and centers of curvature, and a bull's-eye formed upon the outer surface of said lens to produce a more brilliantly illuminated central portion in a light beam from said lens.

22. In a sewing machine, a lens having a plurality of refracting zones and a plurality of total reflecting zones, the upper portion of said lens differing from the lower and each refracting and reflecting zone differing from the others, flutes formed upon the outer surface of said lens, said flutes each comprising in vertical section different curved elements blending straight lines and arcs of circles, whereby an asymmetrical beam pattern is produced.

23. In a sewing machine, a projector comprising: a housing whose upper and lower halves are toroidal surfaces of revolution each having different centers displaced from the axis of revolution and whose inner surface is a reflecting surface, a light source in the axis of revolution of said housing, and a lens flanged inwardly closing the aperture of said housing, a plurality of

refracting zones and a plurality of total reflecting prisms formed upon said lens, said housing producing a general widespread illumination of low intensity surrounding the main portion of a beam from said projector.

24. In combination: a sewing machine, a light projector mounted above said machine, said light projector comprising a light source and a lens with a plurality of refracting and total reflecting zones oriented in such manner as to project the direct light from said source in an elongated concentrated beam onto the area containing the needle position in the table of said sewing machine.

25. A means for illuminating that area of a sewing machine including and surrounding the needle, consisting in a light source mounted on the machine and a prismatic refractor formed to provide annular refracting zones of different curvatures and different centers of curvature to direct the light rays from the light source with maximum intensity upon the needle and the area immediately surrounding the needle.

26. In a light projector, a lens comprising a plurality of refracting zones and a plurality of total reflecting zones, the total reflecting zones being separated by the refracting zones, a light source in the optical axis of said projector, and horizontal flutes formed upon the outer surface of the lens, said reflecting and refracting zones and said flutes being oriented in relation to each other so as to converge the direct light from said light source into an oval beam elongated vertically in two elliptical parts in which the part from one portion of said lens has larger minor and major axes than the respective axes of the part from the other portion of the lens.

PHILIPP A. CULLMAN.
